UNITED STATES PATENT OFFICE.

THOMAS C. JOHNSON, OF NEW HAVEN, CONNECTICUT, ASSIGNOR
WINCHESTER REPEATING ARMS CO., OF NEW HAVEN, CONNECTICUT, A CORPORATION.

FORESTOCK TIP FOR FIREARMS.

SPECIFICATION forming part of Letters Patent No. 768,666, dated August 30, 1904.

Application filed July 2, 1903. Serial No. 164,041. (No model.)

To all whom it may concern:

Be it known that I, THOMAS C. JOHNSON, of New Haven, in the county of New Haven and State of Connecticut, have invented a new and useful Improvement in Forestock Tips for Firearms; and I do hereby declare the following, when taken in connection with the accompanying drawings and the letters of reference marked thereon, to be a full, clear, and exact description of the same, and which said drawings constitute part of this specification, and represent, in—

15 Figure 1, a view partly in side elevation and partly in vertical longitudinal section of a gun provided with my improved forestock tip; Fig. 2, a view in vertical section on the line *a b* of Fig. 1, showing the tip, barrel, and magazine; Fig. 3, a view in transverse section on the line *c d* of Fig. 1, showing the barrel, 20 magazine, and forestock; Fig. 4, a detached view of the tip in front elevation; Fig. 5, a corresponding rear view thereof; Fig. 6, a detached front end view of the magazine.

25 My invention relates to an improvement in forestock tips for that class of firearms which have recoiling barrels, the object being to produce a simple and convenient tip for supporting the forestock independently of the barrel.

3° With these ends in view my invention consists in certain details of construction and combinations of parts, as will be hereinafter described, and pointed out in the claims.

In carrying out my invention as herein shown I employ a chambered tip 2, formed with a transversely-arranged screw-hole 3, receiving a retaining-screw 4, the middle portion of which takes into a semicircular groove 5, formed in an oblong rectangular coupling-lug 6, made integral with and located upon the upper face of the tubular magazine 7 at the forward end of the same, whereby the tip is coupled to the magazine. The sidewise bearing of the screw 4 in the groove 5 holds the tip against longitudinal movement with respect to the magazine, while the endwise bearing of the screw in the groove holds the tip against rotary movement with respect

to the magazine. The tip and magazine further coupled together by the engagement of two abutments 8, located within the tip against the edges of the lug 6, these abutments being the end walls of a passage 9, located in the tip, and connecting the upper and portions of the chamber 10 thereof.

If desired, a centrally-located slot 11 be formed in the tip. It is thus converted, as it were, into an elastic yoke, the two abutments of which may be drawn together by screw 4, so as to bring the abutments firm bearing against the edges of the slot, whereby the tip is held against rotation in respect to the magazine.

The rear edge of the tip is formed with a tenon-recess 12 to receive a tenon 13, formed in the forward end of the forestock 14, rear end of which is formed with a corresponding tenon 15, entered into a tenon-recess 16, formed in the forward end of the gun-frame 17. The upper portion of the forestock is formed with a deep groove 18, receiving the lower portion of the recess 16, barrel 19, which is thus embraced by the forestock as far as required for the protection of the hand of the user from the barrel. The same moves forward and back. The lower portion of the tip is formed with a circular recess 20, receiving the extreme forward end of the magazine, whereby the tip is supported by the magazine, the rear end of which is formed with a threaded shank 21 and screwed securely into a threaded hole 22 in the gun-frame. It will thus be seen that the forward end of the forestock is supported by the tip, which in turn is supported by the magazine, the rear end of which is rigidly secured to the gun-frame. The magazine is provided with a shank 24. The upper portion of the tip is formed with a semicircular clearance-opening 25, the barrel, the lower face of which just fits against the walls of this opening as the barrel moves back and forth. The tip thus extends around, and embraces the barrel as far as required for its support of the forward end of the deeply-grooved barrel-embracing forestock.

It is apparent that in carrying out my invention some changes in the construction herein shown may be made. I would therefore have it understood that I do not limit myself to such construction, but hold myself at liberty to make such changes therein as fairly fall within the spirit and scope of my invention.

Having fully described my invention, what I claim as new, and desire to secure by Letters 10 Patent, is—

1. In a gun, the combination with a gun-frame, of a recoiling gun-barrel, a tubular magazine rigidly secured to the said frame and provided at its forward end with a grooved 15 coupling-lug, a barrel-embracing forestock tip applied to the forward end of the magazine by which it is supported independently of the barrel, a screw passing transversely through the tip and engaging with the said 20 coupling-lug, and a barrel-embracing forestock having its forward end supported by the said tip.
2. In a gun, the combination with the gun-frame, of a recoiling gun-barrel, a barrel-embracing forestock, a barrel-embracing forestock tip for supporting the forward end of the forestock, and a tubular magazine upon the forward end of which the said tip is supported, the said tip having a circular opening 25 adapting it to be applied to the forward end of the magazine and also having a semicircular opening formed in its upper portion to adapt it to embrace the gun-barrel.
3. In a gun, the combination with a gun-

frame, of a recoiling gun-barrel, magazine rigidly mounted in the frame embracing forestock tip having face chambered and formed with notches and adapted to be applied ward end of the magazine which its sole support and shaped to e lower portion of the gun-barrel, a lug located upon the forward end of the magazine and having its edges coacting with said abutments to prevent the tip from falling with respect to the magazine, for securing the tip to the magazine.

4. In a gun-barrel, the combination with a gun-frame, of a recoiling gun-barrel, magazine rigidly mounted in the barrel-embracing forestock tip having face formed with two abutments adapted to be applied to the forward end of the magazine which constitutes its sole support and shaped to embrace the lower portion of the gun-barrel, a coupling-lug located upon the forward end of the magazine a with the said abutments which edges to prevent the tip from falling with respect to the magazine, and means for securing the tip to the magazine.

In testimony whereof I have signed this specification in the presence of two witnesses.

THOMAS C. JOHNSON
